UNITED STATES PATENT OFFICE.

CHARLES HENRY BARROWS, OF ELLENDALE, DELAWARE, ASSIGNOR OF
ONE-FOURTH TO S. F. GARDINER, OF MILFORD, DELAWARE.

SWINGING CHAIR.

SPECIFICATION forming part of Letters Patent No. 643,454, dated February 13, 1900.

Application filed September 14, 1899. Serial No. 730,496. (No model.)

To all whom it may concern:

Be it known that I, CHARLES HENRY BARROWS, a citizen of the United States, residing at Ellendale, in the county of Sussex and State 5 of Delaware, have invented certain new and useful Improvements in Swinging Chairs; and I do hereby declare the following to be a full, clear, and exact description of the invention, such as will enable others skilled in the art to 10 to which it appertains to make and use the same.

My invention relates to improvements in swinging chairs equally applicable for various other analogous articles, as swings, lounging chairs for parlor, lawn, or veranda, or for 15 couches or beds.

It has for its object to greatly simplify the construction and arrangement of parts, including lessening cost of manufacture, and to otherwise promote utility, convenience, 20 and facility in use.

It consists of the detailed construction, arrangement, and combination of parts, substantially as hereinafter more fully disclosed, and specifically pointed out in the claims.

25 In the accompanying drawings, illustrating the preferred embodiment of my invention, Figure 1 is a side elevation. Fig. 2 is a horizontal section. Fig. 3 is a front elevation.

It will be understood that I do not limit myself to details herein, as they may be changed at will without departing from the spirit of my invention and the same yet remain intact and be protected.

In the organization of my invention I provide 35 the usual chair or seat 1 with a sliding or extensible and retractible foot-rest 2, comprising a bar or arm 2^a, slid in a suitable socket or support 3 under the chair for convenient use, and a cross-bar 3^a, fixed to the 40 forward end of said arm.

The chair 1 has suitably connected to it parallel suspending-bars 4 4, suitably braced or connected together, their lower ends being secured to an axial or cylindric cross-rod passing 45 undersaid chair through apertures or resting in bearings secured thereunder. The suspending-bars are arranged alongside of arched brackets 5, secured to the chair-arms,

and 6 6 are adjusting-screws, with their inner ends each provided with a hand-wheel 6^a 50 for its convenient manipulation. Said screws work in screw-threaded apertures 6^b in blocks 7, secured or set in said suspending-bars and terminated at their outer ends in preferably disk-like heads 7^a, bearing against the outer 55 sides of said chair-arm brackets. This arrangement permits of the ready relative adjustment and clamping together of said suspending-bars and chair to vary the angle of adjustment or inclination of the seat or chair 60 to the horizontal to suit the ease or comfort of the occupant.

This chair may be suspended in position in any suitable location, as will be appreciated, by a single spring or two springs, either in a 65 portably-erected frame or from an overhead support.

Having thus fully described my invention, what I claim as new, and desire to secure by Letters Patent, is— 70

1. In a chair of the character described, the combination of a seat or chair, and parallel suspending-bars suitably braced or connected together, with their lower ends secured to a cross-rod or pivot bearing in the under side 75 of said seat or chair and means for the relative adjustment and clamping together of said suspending-bars and chair or seat, substantially as set forth.

2. In a chair of the character described, the combination of a seat or chair and parallel suspending-bars with their lower connecting cross-rod bearing in the under side of said chair or seat, a set or adjusting screw working in a screw-threaded aperture of a block 85 or piece in each of said suspending-bars, and having one end provided with a hand-wheel and its other end terminating in a disk or plate, substantially as set forth.

In testimony whereof I affix my signature 90 in presence of two witnesses.

CHARLES HENRY BARROWS.
